UNITED STATES PATENT OFFICE.

JOHN DANIEL DUNFIELD, OF PETROLIA, ONTARIO, CANADA.

SHOE-TREE.

1,353,327.

Specification of Letters Patent. Patented Sept. 21, 1920.

Application filed July 28, 1919. Serial No. 313,856.

To all whom it may concern:

Be it known that I, JOHN DANIEL DUNFIELD, of the town of Petrolia, in the county of Lambton, in the Province of Ontario, Canada, have invented certain new and useful Improvements in Shoe-Trees, of which the following is the specification.

My invention relates to improvements in shoe trees and the object of the invention is to devise a metal tree which is readily adjustable to suit various sizes of shoes and which may be easily and quickly placed in or removed from the shoe and it consists essentially of the following arrangement and construction of parts as herein after more particularly explained.

Figure 1 is a longitudinal sectional view through the shoe and my device in position therein.

Fig. 2, is a detail view of the strut members connecting the toe and heel pieces of the tree.

Fig. 3, is an enlarged sectional view in line $x-y$ in Fig. 2.

Figs. 4 and 5 are fragmentary detail views illustrating the connection between the strut members.

Fig. 6 is a detail view of the key for securing the strut members in the adjacent position.

In drawings like characters of reference indicate the corresponding parts in the various figures.

1 indicates a shoe. 2 is the metal toe piece 35 of my shoe tree provided with an internal depending lug 3. 4 is the heel piece provided with an internal inwardly extending lug 5. A toe piece 2 fits in the shoe and a heel piece 4 in the heel of the shoe in the 40 usual manner common to various classes of shoe trees. I will now describe the strut connection for connecting the toe and heel pieces together and which forms the subject matter of the applicant's invention. 6 is a 45 bar which is pivotally connected at one end to the lug 5 by a pin 7 and provided at its opposite end with a hole 8 having a rectangular notch 9 cut in the edge of the hole. 10 is a sheet metal bar which is formed in 50 inverted U form, the lower edges of the depending arms of the U being turned inward on themselves at 11 and 12, as shown in Fig.

3 so as to form edges 13 and 14 extending longitudinally of the bar 10. 15 are series of orifices formed in each arm of the U, each 55 orifice corresponding in form to the orifice 8 and each so placed in the bar 10 as to be brought successively into a line with the orifice 8 when the bar 6 is moved longitudinally within the bar 10. The back is provided 60 in one edge with outwardly stamped portions 16 and 17 which rest upon the ledges 13 and 14 and are slidably thereon. The end edges of the depending arms of the U bar 10 are turned inward at 18 and 19 so as to engage 65 with the portions 16 and 17 to prevent the bar 6 being drawn from the bar 10. The end of the bar 10 adjacent to the toe piece 2 is pivotally connected by a pin 20 to the lug 3. 21 is a key the shank of which fits the 70 orifices 15 and 8. The key 20 is provided with a lug 22 extending from the shank and which is adapted to pass through the notch 9 of the orifices 8 and 15 when inserting the key through the orifices 8 and 15. The bars 75 6 and 10 are thus pivotally connected together, the lug 22 being turned out of alignment with the notches 9 so as to prevent its withdrawal. When the shoe tree is inserted 80 in the shoe the bars 6 and 10 are drawn upward into the angular position indicated by the dotted lines in Fig. 1. When the toe and heel pieces are inserted in the shoe the bars 6 and 10 are forced into an alined position, the 85 downward movement being limited by the edge of the bar 6 engaging the base portion of the inverted U bar 10. When withdrawing the tree the reverse of this operation takes place. If the shoe tree is to be used in a larger or smaller shoe all that is necessary 90 to do is to withdraw the key from the orifices 8 and 15 and then move the bar 6 longitudinally within the bar 10 so as to carry the orifice 8 into alinement with another of the orifices 15 of the bar 10; the key is then reinserted. 95

By this description it will be seen that I have devised a very simple form of shoe tree which may be readily adjusted to suit any size of shoe and which is easily withdrawable from and placed in position within the shoe. 100

What I claim as my invention is:

1. In a shoe tree, the combination with a

toe piece and heel piece, of a bar member pivotally connected to the toe piece having inturned edges providing spaced track, surfaces within the member, a second bar member pivotally connected to the heel piece sliding within said first member and provided with projections supported on said track surfaces, and means for pivotally connecting the bar members together.

2. A device according to claim 1 in which 10 the free end of the first mentioned bar member has opposite side portions thereof directed inwardly to engage the sides of the second bar member and thereby coöperate with the projections on the latter to prevent 15 complete separation of the bar members.

JOHN DANIEL DUNFIELD.
